FURNACE

Harvey C. Weller, Toledo, Ohio, assignor to Surface Combustion Corporation, Toledo, Ohio, a corporation of New York

Application August 18, 1937, Serial No. 159,747

14 Claims. (Cl. 263—8)

The present invention relates to tunnel type furnaces through which the work is passed in a path which is U-shape in plan and the object of the invention is to provide for the heating 5 of the work by fuel fired radiant tubes arranged in a novel manner to the end that the highest temperature may be at the return bend end of said path with gradually decreasing temperature from that end to the work entering end of the 10 furnace.

In the drawings, wherein the preferred form of the invention is disclosed,—

Fig. 1 is a vertical longitudinal sectional view of a furnace embodying the present invention; 15 the view being along line 1—1 on Fig. 2;

Fig. 2 is an enlarged horizontal section of the furnace shown in Fig. 1 with an intermediate portion omitted;

Fig. 3 is a vertical sectional view taken substantially on line 3—3 of Fig. 2;

Fig. 4 is a sectional detail view of a burner;

Fig. 5 is a sectional detail view of an eductor;

Fig. 6 is a vertical longitudinal sectional view of a furnace embodying a modified form of the 25 invention;

Figs. 7, 8 and 9 are, respectively, vertical cross sections along lines 7—7, 8—8 and 9—9 of Fig. 6, and

Fig. 10 is a horizontal sectional view of a furnace embodying another form of the invention.

Referring to Fig. 1, the furnace illustrated is of the type having a heating zone 10 at an elevated end of a relatively long tunnel through which the work is passed in a path which is U-shaped in plan, the return bend of said path being in said zone, the work being moved along said path by an overhead conveyor comprising a series of hanger rods 11 which extend through a continuous slot in the furnace roof, the incoming work being preheated by the outgoing work.

Extending lengthwise through the tunnel along that lateral half which constitutes the path for the incoming work are a set of wall tubes 12 and a set of floor tubes 13. Also extending lengthwise 45 through the tunnel is a second set of floor tubes 14, these tubes extending through the other lateral half of the heating zone 10 and then extending over into the same lateral half of the tunnel as the other tubes, as indicated at 14a, it being noted that except in the heating zone 50 there are no tubes in that lateral half of the tunnel through which the outgoing work passes.

For convenience of description, that side portion of the tunnel between the heating zone 10 55 and the work intake end of the tunnel will

sometimes be called the preheating zone or portion since it is in that portion that the incoming work is preheated, and the adjacent side portion will sometimes be called the cooling zone or portion since it is in that portion that the outgoing work gives up heat to the incoming work. All of said tubes are fired at one and the same end of the furnace, namely, outside of the end wall 15 at the closed end of the tunnel as indicated at 16. The exhaust end of all of said tubes is at 10 the opposite end of said tunnel as indicated at 17.

The heating zone 10 is centrally divided by a vertical partition wall 18. Disposed along this wall at each side thereof is a heating tube 19 of hairpin type whose fuel intake end 19a extends 15 through the floor of the tunnel and whose exhaust end 19a extends through the roof of the same. Also disposed in the heating zone along the side wall of the tunnel is a hairpin type tube 20 whose intake and exhaust ends both extend 20 through the end wall 15 of the tunnel. By thus providing the heating zone 10 with a plurality of heating tubes, heat is uniformly applied to the work as it passes therethrough.

Each of various heating tubes described is independently fired, the firing system being the same for each tube. At the fuel intake end of 25 each tube is a burner indicated by the letter A, of the type shown in Fig. 4 and at the exhaust end of each tube is an eductor indicated by the letter B, of the type shown in Fig. 5. For purposes of the description the letter T indicates 30 the tube to be fired. The burner comprises a fuel delivery tube 21 to which fuel gas is supplied by a pressure gas supply pipe 22 having 35 a regulating valve 23. The fuel tube 21 is shown as extending a substantial distance into the inlet end of the heating tube T to compensate for the thickness of the furnace wall 16. The fuel tube 21 is of comparatively large diameter without any constriction at its discharge end such as would interfere with the projection of a fuel stream for a substantial distance into the heating tube. Surrounding the fuel tube 21 and spaced 40 therefrom is a tube 24 to which is fed a premixed supply of combustible gases under pressure through pipe 25 having a regulating valve 26. Near the outlet end of tube 24 is a ring 27 through which the fuel tube 21 passes and which is provided with a plurality of small passages 45 through which the mixture supplied to tube 24 flows.

The fuel tube 21 extends beyond the tube 24 and the space between the two tubes at the discharge end of the ring 27 forms an annular com- 50

bustion chamber 28 for the mixture flowing through the ring. The outer ends of the tubes 21 and 24 become highly heated and along with the high temperature gases issuing from said chamber 28 constantly insure ignition of the fuel issuing from the inner tube 21.

Air to support combustion of the fuel issuing from tube 21 is induced to enter the heating tube T at its fuel intake end by the eductor shown in Fig. 5 and located at the discharge end of the heating tube. Said eductor comprises a jet orifice nozzle 29 positioned to discharge into an eductor tube 30 forming in effect an extension of the heating tube. A fluid pressure supply pipe 31 is provided with a regulating valve 32 to permit the entraining effect to be adjusted as desired. As the strong induced draft through the heating tube tends to pull the flame away from the fuel tube 21, thus causing it to be extinguished, the previously described combustion chamber 28 constantly insures ignition of the fuel and air where they intermix in combustible proportions.

The type of radiant tube heating element T above described provides the means for heating the heating zone 10 in the desired manner due to the fact that the fuel is caused to burn within the tube for a substantial portion of its length. As the entraining effect of the eductor tends to draw the flame and thus the heat toward the outlet end of the radiant tube it is to be noted that the heat is radiated in a gradually diminishing degree toward the outlet end of the tube. Thus, high heat concentration takes place in the zone 10 which is in effect a heat pocket undisturbed by gas or air currents due to its elevated position, while the remainder of the tunnel serves as a heat exchange zone wherein heat is radiated from the outgoing hot articles to the incoming cold articles and wherein heat is radiated from the tubes 14a that cross over to the preheating portion of the tunnel to preheat the incoming articles. The cooler portions of the radiant tubes also radiate sufficient heat to effect preheating of the incoming articles.

By avoiding the use of the radiant tubes in the outgoing portion of the tunnel, the cooling portion of the tunnel permits radiation to take place from the outgoing articles, thus enabling the articles to be gradually cooled as they approach the discharge end of the tunnel structure. To further insure a high concentration of temperature in the heating zone 10, the hairpin type radiant tubes 19 and 20 are used.

In operation, it will be understood that when the furnace is used as an enameling furnace, the articles are suitably enameled or coated as by dipping, spraying or otherwise and subsequently fed into the tunnel from the right as viewed in Fig. 1. As the articles pass into one side of the heating zone and arcuately around the partition 18 and through the other side of the zone they are highly heated to the desired temperature to take the enamel coating. Passing from the heating zone, the articles radiate heat to the incoming articles. As the cooling zone is free of heating means, the articles radiate their heat and are cooled comparatively quickly as they approach the discharge end of the tunnel, from which the articles are carried into the outside atmosphere to further cool.

In the modified form of the invention shown in Figs. 6-9, the heating zone is indicated at 10' and the central vertical partition wall at 18'. In each portion of the heating zone 10' are arranged two side wall tubes and a floor tube. The

side wall tubes in the incoming portion of the tunnel are indicated at 40 and 42 and the floor tube at 41 and the side wall tubes in the outgoing portion at 43 and 45 and the floor tube at 44. Each of these tubes in the heating zone is doubled back upon itself, as indicated at 46, for some distance, and the leg thus formed passing out of the heating zone through the floor thereof and constituting the firing end 48 of the tube. This arrangement has the advantage of practically doubling the heat radiating area of the tubes in said zone and moreover the bend of the tube serves very materially to accelerate combustion due to rapid intermixing of the air and fuel at that point, which produces a hot spot in the tube and intensifies the heat radiation adjacent the closed end of the tunnel.

The firing end of each tube is provided with a burner A of the type shown in Fig. 4 and the exhaust end of each tube is provided with an eductor B of the type shown in Fig. 5.

All of the tubes as they leave the heating zone extend for a portion of their length adjacent the floor of the tunnel below the path of the incoming work, and those in the work-outgoing side of the heating zone cross over to the opposite side of the tunnel and are positioned therealong adjacent one side of the path of the incoming work. Thus, the incoming work receives heat from the tubes on the wall and the outgoing work respectively. As the incoming work is carried toward the heating zone the temperature is gradually increased to reach a maximum in the heating zone where the work is substantially surrounded by heating elements. In Figs. 6, 8 and 9, those numerals having the suffix "a" indicate the position of the tubes 43, 44 and 45 in the preheating zone of the tunnel.

In the modified form of the invention shown in Fig. 10, the heating zone 50 is of arcuate shape and comprises an outer arcuate wall 51 and an interior centrally located partition or pillar 52 having an arcuate portion defining the incoming and outgoing portions of the heating chamber. The radius of curvature of the arcuate portion of the heating zone is substantially greater than half the width of the straight portion of the tunnel to provide an enlarged circular portion for the return bend end of the U-shape path of the work.

A set of tubular heating elements 54 of substantially hook-shape are arranged adjacent the floor of the heating zone 50, and have their inlet ends 55 projecting through the wall 51 adjacent the discharge end of the heating zone and provided with burners A of the type shown in Fig. 4. From the heating zone the heating tubes extend along the floor of the preheating zone of the tunnel and at their discharge ends are provided with eductors B of the type shown in Fig. 5. If desired, additional heating tubes may be arranged adjacent the wall 51, as well as along the floor, to provide additional heat in the heating zone. The shape of the tubes 54 lend themselves to comparatively rapid and intense heat radiation as the curvature thereof causes the intermixing of air and gas soon after entering the tubes, and high temperatures may thus be produced in the zone.

What I claim is:

1. In a furnace, the combination of a recuperative chamber and a heating chamber forming a tunnel, means for moving work into and out of the tunnel in a U-shaped path, the return bend of said path being in the heating chamber and

the legs of said path extending through the recuperative chamber, means for producing a rising temperature gradient in the tunnel in direction toward the heating chamber, said last named 5 means comprising a heating tube within the recuperative chamber lengthwise thereof, a substantial portion of said tube being in closer heating proximity to the incoming work than to the outgoing work, and means for causing heating 10 gases to flow through said tube in direction opposite to that of the incoming work.

2. In a furnace, the combination of a recuperative chamber and a heating chamber forming a tunnel, means for moving work into and out of 15 the tunnel in a U-shape path, the return bend of said path being in the heating chamber and the legs of said path extending through the recuperative chamber, means for producing a rising temperature gradient in the tunnel in direction 20 toward the heating chamber, said last named means comprising a heating tube having a substantial portion of its length within the heating chamber and which extends into the recuperative chamber along the work-incoming side thereof, 25 and a burner firing into that end of the tube nearest the heating chamber.

3. In a furnace, the combination of a recuperative chamber and a heating chamber forming a tunnel, means for moving work into and out of 30 the tunnel in a U-shape path, the return bend of said path being in the heating chamber and the legs of said path extending through the recuperative chamber, means for producing a rising temperature gradient in the tunnel in direction 35 toward the heating chamber, said last named means comprising a heating tube which extends for a portion of its length along the work-incoming side of the recuperative chamber and then passes through the heating chamber and out of 40 the latter chamber adjacent the work-outgoing side thereof, and a burner firing into that end of the tube which extends out of the heating chamber.

4. In a furnace, the combination of a recuperative chamber and a heating chamber forming a tunnel, means for moving work into and out of 45 the tunnel in a U-shape path, the return bend of said path being in the heating chamber and the legs of said path extending through the recuperative chamber, means for producing a rising temperature gradient in the tunnel in direction 50 toward the heating chamber, said last named means comprising a hook-shape heating tube, the longer leg of said tube extending along the work-incoming side of the recuperative chamber, the hook portion of said tube being in the heating chamber, and a burner firing into the hook end 55 of the tube.

5. In a furnace, the combination of a recuperative chamber and a heating chamber forming a tunnel, means for moving work into and out of 60 the tunnel in a U-shape path, the return bend of said path being in the heating chamber and the legs of said path extending through the recuperative chamber, means for producing a rising temperature gradient in the tunnel in direction 65 toward the heating chamber, said last named means comprising a hook-shape heating tube, the longer leg of said tube extending along the work-incoming side of the recuperative chamber, the hook portion of said tube being substantially coincident with the return bend of said U-shape path, and a burner firing into the hook end of 70 the tube.

6. In a furnace, the combination of a recuperative chamber and a heating chamber forming a tunnel, means for moving work into and out of the tunnel in a U-shape path, the return bend of said path being in the heating chamber and the 5 legs of said path extending through the recuperative chamber, means for producing a rising temperature gradient in the tunnel in direction toward the heating chamber, said last named means comprising a heating tube which extends for a 10 portion of its length along the work-incoming side of the recuperative chamber and then passes laterally across the latter chamber and into the heating chamber, and a burner firing into that end of the tube nearest the heating chamber. 15

7. In a furnace, the combination of a recuperative chamber and a heating chamber forming a tunnel, means for moving work into and out of the tunnel in a U-shape path, the return bend of said path being in the heating chamber and the 20 legs of said path extending through the recuperative chamber, means for producing a rising temperature gradient in the tunnel in direction toward the heating chamber, said last named means comprising a heating tube which extends for a 25 portion of its length along the side wall of the recuperative chamber nearest the incoming work and then passes along the floor of the recuperative chamber below the incoming work and then passes laterally across the latter chamber and 30 into the heating chamber, and a burner firing into that end of the tube nearest the heating chamber.

8. In a furnace, the combination of a walled structure forming a tunnel which is closed at one 35 end and open at its other end, a heating tube disposed adjacent one side wall of the tunnel, a second heating tube having an end portion disposed adjacent the other side wall and a portion 40 extending laterally toward said first heating tube, and means for supplying heating gases to one end of each of said tubes.

9. In a furnace, the combination of a walled structure forming a tunnel which is closed at 45 one end and open at its other end, a set of heating tubes disposed adjacent one side wall of the tunnel, a second set of heating tubes having end portions disposed adjacent the other side wall and portions 50 extending angularly toward said first set of tubes, and means for supplying heating gases to one end of each of said tubes.

10. In a furnace, the combination of a walled structure forming a tunnel which is closed at one end and open at its other end, a heating tube disposed adjacent one side wall of the tunnel, and a 55 second heating tube having end portions disposed adjacent opposite side walls and an intermediate portion extending laterally of said tunnel, said tubes having U-shape portions disposed adjacent the closed end of said tunnel.

11. In a furnace, the combination of a walled structure forming a tunnel which is closed at one end and open at its other end, a set of heating tubes disposed adjacent one side of the tunnel, a second set of heating tubes having end 65 portions disposed adjacent the other side of the tunnel and portions extending laterally toward said first set of tubes, and a plurality of heating tubes of U-shape configuration disposed adjacent 70 the closed end of the tunnel and between said first and second sets of tubes.

12. In a furnace, the combination of a structure forming a tunnel having a heating zone at one end and open at its other end for the ingress 75

- and egress of work, means for moving the work through the tunnel in a U-shape path of which the return bend is in said heating zone, and means for producing heat in said zone comprising a 5 U-shape tube between the legs of and inwardly of the return bend of said path and whose ends extend out of said zone through the roof and floor of the tunnel, and a burner firing into one end of said tube.
- 10 13. In a furnace, the combination of a structure forming a tunnel which is closed at one end and open at its other end for the ingress and egress of work, a conveyor for conveying the work into and out of the tunnel along a U-shape path 15 of which the return bend is at the closed end of the tunnel, a partition spaced from the closed end of said tunnel and around the end of which the work is passed, a heating tube disposed on

each side of said partition, one of said tubes converging toward the other adjacent the other end of the partition to be in heating proximity to the incoming work.

14. In a furnace, the combination of a structure forming a tunnel which is closed at one end and open at its other end for the ingress and egress of work, means for moving the work into and out of the tunnel along a U-shape path of which the return bend is at the closed end of the 10 tunnel, a heating tube disposed along one side of the tunnel and in heating proximity to the incoming work, and a heating tube coextensive with said first tube throughout a major portion of its length and diverging into heating proximity to the outgoing work adjacent the closed end of the tunnel.

HARVEY C. WELLER.
